UNITED STATES PATENT OFFICE.

CARL PUFF, OF SPANDAU, GERMANY.

PERCUSSION-FUSE.

No. 910,575.

Specification of Letters Patent. Patented Jan. 26, 1909.

Application filed January 4, 1907. Serial No. 350,810.

To all whom it may concern:

Be it known that I, CARL PUFF, engineer, a subject of the King of Prussia, residing at Spandau, Lindenauer, No. 32, in the Kingdom of Prussia, Germany, have invented certain new and useful Improvements Relating to or Connected with Percussion-Fuses, of which the following is a full, clear, and exact description.

10 This invention relates to that class of percussion fuses or double acting fuses in which the priming part of the percussion fuse, and therefore the bursting charge of the projectile, is exploded according to the 15 adjustment of the fuse, either directly on the impact of the projectile, or the ignition of the bursting charge is by means of a mechanical device provided for that purpose delayed until the projectile has penetrated 20 into the object it was aimed at, for the purpose of obtaining a mining effect. The characteristic feature of this fuse consists in that a retarding device, operated by altering the position of or connecting or 25 disconnecting any suitable part of the fuse, is arranged in the fuse, which, with delayed ignition, holds the ignition parts (generally a percussion cap and a needle) apart from each other until the projectile has penetrated 30 a certain distance into the object at which it was aimed, and only then the ignition parts, by impact, friction or other means (in certain circumstances even electrical means) effect the delayed ignition. The retarding 35 device is disconnected if the projectile is to be detonated immediately on encountering the object aimed at.

Now the present invention has for its object the improved construction of a fuse 40 in which the ignition parts, which are held locked by means of any suitable connectible and disconnectible locking or checking means and released on the impact of the projectile, are exposed to spring pressure or 45 lever power; furthermore the arrangement is preferably such that the locking devices are arranged on the ignition part and, by the displacement of a suitable fuse part, can be brought into such a position that they engage 50 with a fuse part exposed to spring pressure, if the ignition part has to be ignited by the striking effect of the spring and has to ignite after a certain delay.

In the accompanying drawings, Figure 1 55 is a longitudinal section of a percussion fuse constructed according to the present in-

vention and illustrating the positions of the parts after firing of the projectile and previous to striking the mark. Fig. 2 is a similar view to Fig. 1 illustrating the positions of 60 the parts after the projectile has struck the object. Fig. 3 is a longitudinal section of part of the fuse with the firing bolt turned to a position at right angles to that shown at Fig. 1 and Fig. 4 is a transverse section 65 taken on the line A—B of Fig. 1. Fig. 5 is a longitudinal section with the parts in their initial position.

In the several figures like parts are indicated by similar letters of reference. 70

The firing bolt *t* is rotatively arranged in the casing *a* and in the normal position of the parts is secured against longitudinal movement by spring arms *a* or detents *k* provided with lugs or shoulders *k*¹ and embraced by a ring *f*. The rectangular needle *c*¹ projects through the screw cap *b* into the firing bolt *t* which needle is fixed with the rotatable adjusting part *c*. The ring *f* and the socket or sleeve *h* are arranged in 80 the casing *a* in such manner as to be longitudinally displaceable.

The ring *f* and the socket or sleeve *h* are pressed forward by the spring *i* and the sleeve *h* is provided on its interior surface 85 with recesses *h*¹ (Fig. 1) in which the pawl like spring tongues *s* (Fig. 3) mounted upon the firing bolt *t*, engage, when by adjusting the part *c* according to special marks and lines arranged on the fuse, the rectangular 90 needle *c*¹ and the firing bolt *t* rotatively connected with it is so turned, that the pawl like tongues *s* arranged on the firing bolt are situated opposite the recesses *h*¹. The spring *i* (Fig. 3) tends to drive forward the pawl like 95 arms *s* and the firing bolt *t* together with the socket or sleeve *h* so that the percussion cap *m* flies against the needle *c*¹ and is exploded, but the firing bolt *t* is prevented from longitudinal movement by the arms or detents *k* 100 with their shoulders *k*¹ as long as the ring *f* remains in its position. (Fig. 1).

Before the projectile is fired the parts are in the position shown in Fig. 5, in which position the sleeve *h* is held fixed by pins *e* of copper or other soft metal. A disk *d* having arms *d*¹ is also in the position shown in Fig. 5. Just before firing the disk *d* is turned so that its pins *d*¹ are opposite notches in the ring *f*, so that this ring can move forwardly 110 when the projectile strikes the mark as will be described.

When the projectile is fired the inertia of the ring *f* and sleeve *h* is sufficient to cause these parts to move backward relatively to the body of the fuse which they do until the 5 sleeve *h* is caught by the pawl like tongues *s*. The position of the parts is then as indicated in Fig. 1. When the projectile reaches the mark the ring *f* flies forwardly as shown in Fig. 2, thus permitting the spring arms or 10 detents *k* to move laterally so that their shoulders *k*¹ release the firing bolt *t*. This permits the sleeve *h* to move forwardly under the expansion of its spring *i*, carrying with it the firing bolt *t* by reason of the fact that the 15 pawl like tongues *s* fixed to the firing bolt are still engaged by the ring *h*, so that the firing bolt *t* is thrust forwardly by the spring. This retardation corresponds to the time which elapses until the above described 20 movements have been completed, during this time however the projectile penetrates deeper into the object and is detonated within the object itself.

If the firing is to be effected without retardation, the pawl like tongues *s* are so adjusted by turning the part *c* that they are not situated opposite the recesses *h*¹ but opposite the smooth walls of the sleeve or socket *h*. The pawl like tongues *s* cannot then hold the 30 sleeve or socket *h* in the retracted position but it is pushed forward with the ring *f* by means of the spring *i* during the flight of the projectile, so that the firing bolt *t* is released and is not prevented from igniting the cap on 35 the impact of the projectile.

In the present form of construction the percussion cap *m* is arranged in the movable part but it can alternatively be arranged in the fixed part as will be readily understood.

40 The invention preferably includes an ignition charge which is adapted to move forwardly in the fuse so that it surrounds an exploding capsule *o*. The capsule *o* is held in a centrally located member *r*, and the ignition charge *q* is contained within a cylindrical case surrounding the member *r* and normally held in the position shown in Figs. 1 and 5. It is held in this position by a two- 45 armed spring *p* which is preferably connected to the cylindrical case, which is formed with noses *p*¹ engaging notches or recesses *g*³ in the body of the fuse. The ring *f* has connected with it at opposite points two throw-out rods *g* which lie along the inner sides of 50 the fuse wall and which are provided with pointed ends normally lying between the noses *p*¹ of the spring *p*. Upon firing the projectile as the ring *f* moves rearwardly, the throw-off rods *g*, which partake of this movement, press the noses *p*¹ of the spring *p* out of engagement with the recesses *g*³. This movement continues until the shoulders *g*² formed on the rods pass the rear of the spring *p* in which position the ring *f* and ignition 60 charge *q* are connected together. The rods 65

g are of greater thickness forwardly of the noses *g*² than at their points, so that the noses *p*¹ are held out of engagement with the notches *g*³ when the shoulders *g*² pass behind them. 70

When the mark is reached by the projectile and the ring *f* flies off, the ignition charge *q* moves forwardly with it to the position shown in Fig. 2, so that when the percussion cap *m* and exploding capsule *o* are fired the 75 ignition charge is in proper position.

When no retarding effect is desired, and the parts are adjusted so that the pawl like tongues *s* are out of position as hereinbefore described, the spring *i*, which in this case 80 presses both the sleeve *h* and the ring *f* forwardly, acts through the ring to move the ignition charge *q* forwardly during the flight of the projectile. When the mark is reached, the firing bolt *t*, which has theretofore retained its initial position, is moved forwardly by its inertia, firing the cap *m*. 85

The pawl like tongues *s* which in the present form of construction always press outward with spring action, might also be so arranged in the firing bolt *t* that they are first pressed outward by shoulders arranged on the rotary needle *c*¹ when it is desired to fire with retardation. 90

What I claim as my invention, and desire to secure by Letters Patent is:

1. A percussion fuse having a firing part adapted to be actuated by impact, means for retarding the operation of such part for a period of time after impact, and means for throwing such retarding means out of operation, whereby said fuse may act directly upon impact. 100

2. In a percussion fuse, means for firing the fuse by impact, and a mechanically acting retarding device adapted to delay the firing of the fuse for a period of time after impact, such retarding device being adapted to be connected or disconnected before firing. 105

3. In a percussion fuse, means for firing the fuse by impact, a mechanically acting retarding device adapted to delay the firing of the fuse for a period of time after impact, such retarding device being adapted to be connected or disconnected before firing, and 110 an igniting charge adapted to be moved forwardly into position after the projectile is fired. 115

4. A fuse having a firing bolt, means for holding such bolt in fixed position, a ring adapted to release such means, a spring-controlled sleeve, and catches connected with the firing bolt adapted to hold said sleeve in retracted position. 120

In testimony whereof I have hereunto set my hand in presence of two subscribing witnesses. 125
